CASKET SEAL STRUCTURE

Benjamin F. Paul, Elwood, Ind.; Mildred H. Paul
administratrix of said Benjamin F. Paul, deceased

Application September 22, 1949, Serial No. 117,172

4 Claims. (Cl. 27—17)

1

This invention relates to a casket seal structure. The chief object of the present invention is to seal the casket lid to the casket body by means controlled externally of the casket.

The chief feature of the present invention resides in associating a one-piece casket lid or top with a seal that extends entirely around the body of the casket, the lid when closed bearing upon said seal.

Other objects and features of the invention will be set forth more fully hereinafter.

The full nature of the invention will be understood from the accompanying drawings and the following description and claims:

In the drawings:

Fig. 1 is a perspective view of a one-piece top type casket, the seal control being disposed at the casket end as illustrated.

Fig. 2 is an enlarged end elevation of the said control and a portion of the end of the casket body.

Fig. 3 is a transverse sectional view taken on line 3—3 of Fig. 2 and in the direction of the arrows.

Fig. 4 is a somewhat similar view of a slightly modified form of the invention.

In Fig. 1 of the drawings 10 indicates a casket body having the usual carrying handles, bars, etc., attached thereto and 11 shows a one-piece lid. When a half couch effect is desired, a supplemental half-length interior lid may be provided. Mention is herein made thereof solely for the purpose of pointing out that it can be included or omitted as desired.

Peripherally enveloping the top of the body is 35 a shield member 12 having an inturned lower flange 13 and an upper inturned shorter flange 14. This shield is suitably secured to the body and herein screw 15 serves such purposes. Spot welding, and the like may be utilized if desired.

The upper portion of the casket body includes the frame member 16 partially masked by the body sheet metal having outer upper ledge portion 17, inwardly directed top face 18 and downwardly turned internal flange 19 exposing portion 16 for tacking and like purposes.

The casket lid 11 has outwardly and downwardly directed portion 20 with depending skirt 21 and inturned bottom face 22 terminating in upturned inner flange 23, same comprising a retainer for the frame 24 and exposing it for tacking purposes. Since the arc upon which the casket lid edge 25, which can be a bead, swings is of quite large radius only slight clearance is required between said lid edge and flange edge 14.

2

An angle sectioned sealing cushion strip of rubber or rubber like material having horizontal portion 26 and vertical portion 27 is provided. It extends entirely around the body of the casket. Portion 26 rests upon face 18. Portion 27 is backed by a resilient spring-like steel strip 28 that has straight runs along the sides and ends and has substantially square corners. Strip 28 is so formed that when viewed in plan it has a rectangular outline and is normally biased toward enlargement of that outline. The rubber strip portion 27 is suitably secured to said metal strip 28 as by adhesive or other types of bonding agents.

15 Note that this metal strip 28 is trapped within the upstanding masking portion 12 and the in-turned flange 14 thereof and by flange 18. When the lid 11 is lowered, its lower face 22 bears upon the peripheral sealing gasket portion 26 which bears upon top face 18. Hence a wide seal is provided.

Fig. 3 shows the lid lowered and peripherally gripped and sealed. At an end of the casket the masking portion 12 is interrupted or notched out as at 30 as shown in Figs. 1 and 2. This exposes the ends 29 of the steel strip 28 and the vertical cushion seal portion 27.

One end of strip 28 mounts a hook 32 and bracket 33. The other end thereof mounts bracket 34 that pivotally mounts finger lever 35 carrying locking loop 36 as shown. Loop 36 is adapted to engage hook 32 and be locked over center when finger lever 35 is disposed parallel to the strip which carries it.

When so locked the metal band 28 is tautened about the lower ledge of the lid and clamps the same in lid-body locked position with the seal 27 therebetween as well as seal 26.

Whenever it is desired or required to constrain seal portion 27 and steel strip 28 outwardly, there may be provided as at the corners the L-sectioned spring fingers 37, see Fig. 4, the upper end 38 of which is welded in masked relation to the under face of flange 14. This finger extends into cushion 27 and is covered thereby. It tends to dispose the band and seal 27 in outward position. When clamped, however, these fingers yield inwardly under such clamping action.

50 A key lock can be applied to each toggle lock to prevent unauthorized opening of the toggle thereby locking the lid and body together.

While the invention has been illustrated and described in great detail in the drawings and foregoing description, the same is to be con-

sidered as illustrative and not restrictive in character.

The several modifications described herein as well as others which will readily suggest themselves to persons skilled in this art, all are considered to be within the broad scope of the invention, reference being had to the appended claims.

The invention claimed is:

1. In a casket having a body section and a lid section therefor, the combination therewith of a mask secured to said body section and projecting thereabove, said mask substantially encircling said body section and terminating in an inwardly directed flange, said lid section when closed being telescopically received by said mask, said lid section when closed together with said mask and said flange defining a space, combined clamping and sealing means encircling said lid portion when in closed position and disposed within said space, a portion of said sealing means extending horizontally inwardly and lying between said lid and body sections, and externally exposed means connected to said clamping means for tautening said clamping and sealing means about said lid section.

2. In a casket having a body section and a lid section therefor, the combination therewith of a mask secured to said body section and projecting thereabove, said mask substantially encircling said body section and terminating in an inwardly directed flange abutting said lid section when in closed position, said lid section when in closed position together with said mask and said flange defining a space, combined clamping and sealing means encircling said lid section when in closed position, said clamping means comprising a resilient metal strip disposed within said space in proximity to said

mask, said sealing means comprising a rubber-like sealing cushion having a vertically extending portion and a horizontally disposed portion, said vertically disposed portion being secured to the inner face of said strip and lying within said space, the horizontally disposed portion of said cushion lying between said lid and body sections, and externally exposed means for tautening said clamping and sealing means about said lid section.

3. In a casket having a body and a full length lid, the combination therewith of a mask secured to said body and projecting thereabove, said mask substantially encircling said body section and terminating in an inwardly directed flange, said lid when closed being telescopically received by said mask, a cushion type seal and metal strip device disposed in close proximity to said mask and substantially filling the space defined by said lid when in closed position together with said mask and said flange, said seal having a portion extending inwardly and lying between said lid and body, and means for tautening said device about said lid when said lid is closed.

4. A casket structure as defined by claim 3 wherein there is provided yielding means normally biasing said device towards mask engagement to facilitate lid closing and being yieldable when said device is tautened into lid engagement.
